UNITED STATES PATENT OFFICE.

JAMES C. WOODSON, OF EAST PITTSBURGH, PENNSYLVANIA, ASSIGNOR TO WESTINGHOUSE ELECTRIC & MANUFACTURING COMPANY, A CORPORATION OF PENNSYLVANIA.

ELECTRIC FURNACE.

Application filed June 23, 1925. Serial No. 38,981.

My invention relates to electric furnaces and particularly to resistor-supporting means therefor.

An object of my invention is to provide 5 a relatively simple, efficient and easily removable hanger block for supporting a resistor member.

In practicing my invention, I provide an 10 elongated member of overhung channel section, located in a wall of the furnace, and a plurality of hanger blocks, having a laterally-extending end portion fitting into the groove in said member and having a forwardly extending portion for receiving and 15 supporting a depending resistor member.

A modified form of hanger block has a 20 relatively narrow lateral end portion fitting into the overhung groove and insertible therein and removable therefrom in a position angularly disposed from the normal operative position.

In the single sheet of drawings,

Figure 1 is a view, in vertical longitudinal section, of a furnace embodying my invention,

Fig. 2 is a view, in front elevation, of a member of overhung channel section comprising part of the device embodying my invention,

Fig. 3 is an end view thereof,

Fig. 4 is a view, in side elevation, of a hanger block embodying my invention,

Fig. 5 is a view, in rear elevation, of the hanger block of Fig. 4,

Fig. 6 is a top plan view thereof,

Fig. 7 is a rear end view of a modified form of hanger block,

Fig. 8 is a view in side elevation of a spacer block, and

Fig. 9 is a view in front elevation of the spacer block.

An electric resistance furnace 11 comprises a plurality of walls 12 that are built up of suitable bricks or blocks of a heat-insulating and high-temperature resisting refractory material usually employed in the furnace art. The bricks or block constituting the respective walls are so disposed that they enclose a furnace chamber 13 of any suitable or desired contour and dimensions. As the particular construction and arrangement of the furnace structure proper constitutes no part of my invention, it is illustrated generally only.

Each of the substantially vertical walls 55 that are to have an extended resistor member associated therewith are provided with a groove 14 extending substantially horizontally, in the inner face thereof. Members 15 of a refractory electric-insulating material and of substantially overhung channel shape in lateral section, are located in the respective grooves. The members 15 may be of any desired dimensions laterally thereof, the main consideration being that the 60 groove 16, of substantially T-shape provided therein, shall be large enough to permit of locating therein a hanger block for a resistor member, to be hereinafter described in detail, that shall be of sufficient 65 strength to support the same.

The front overhanging wall portions 17 and 18 should also be of sufficient thickness to provide the necessary strength to support 70 a resistor-supporting member. Each of the 75 members 15 has the overhanging portion 17 and 18 cut away at one end thereof as indicated by the numeral 19 at the right hand end of the member 15 illustrated in Fig. 2 of the drawings, for a purpose to be hereinafter 80 set forth in detail.

A plurality of refractory hanger blocks or resistor-supporting members 21 severally comprise an intermediate portion 22 that is preferably of substantially circular shape 85 and that has attached thereto at the rear end thereof, a laterally expanded portion 23 having upper and lower arcuate surfaces designated by the numerals 24 and 25 respectively. The diametral dimension between 90 these two surfaces is substantially the same as the height or width of the main portion of the groove 16 as it is intended that the portion 23 shall be located within the groove 16.

The sides of the portion 23 are parallel, as is shown more particularly in Fig. 5 of the drawing, the distance therebetween laterally of the intermediate portion 22 being such that the hanger blocks are spaced apart a 100 predetermined distance, which distance determines the spacing between the individual portions of a resistor member that is to be supported thereby. An expanded front portion 26, integral with the portions 22 and 23 105 is provided, and may have the edges thereof of rounded or of wedge shape. The surfaces 24 and 25 may, however, be made

parallel, in which case, they will prevent any turning movement of the hanger blocks in the member 15.

A resistor member 27, here illustrated as 5 comprising a ribbon of a suitable resistor material, such as nichrome, is preformed to comprise a plurality of integral loops and the upper portions thereof are adapted to be located on the front part of the portion 22 10 immediately back of the portion 26, as is illustrated particularly in Fig. 1 of the drawing.

As it is desirable that the adjacent lower 15 end portions of the resistor member be prevented from operatively engaging each other during the operation of the furnace, I provide lugs or projecting members 28 that may be suitably inserted in and secured to the wall of the furnace. These projections are 20 of a refractory electro-insulating material.

Fig. 7 illustrates a modified form of hanger block 29 which differs from that illustrated in Figs. 4 to 6 inclusive, more particularly in that the rear and laterally extending portion 31, that is to be located in the groove 16, is made narrower, the width 25 laterally thereof being such that it may be inserted in, and removed from, the groove 16 between the overhung portions 17 and 18. It all other respects, it is of substantially 30 the same construction as was hereinbefore described in connection with the member 21.

Spacer members 32 are provided to cooperate with, and be located between adjacent members 29 and each comprises a relatively narrow portion 33 that is adapted to be located in the rear or main portion of the slot 16 and a forwardly extending portion 34, the thickness of the two portions being 40 the same and being such as to provide the proper spacing between adjacent hanger blocks.

In using the hanger blocks 21, they are inserted in the groove 16 by first placing the 45 rear portion 23 in the end portion 19 thereof and then moving them longitudinally of the member 15 and laterally of their own length one after the other until the proper number of hanger blocks has been located therein 50 and until they extend closely adjacent to the end portion 19. Any suitable means, such as a mass of initially plastic refractory material, may be employed to fill up the space 19 in order to prevent any movement of the 55 hanger blocks into the space 19 and thus permit of their falling out of engagement with the member 15. It is of course also possible to employ a molded block fitting into the portion 19 instead of an initially plastic mass 60 of material.

When the hanger block 29 is employed, it is possible to insert all but one or two of the last hanger blocks into the member 15 by turning them 90° from their normal operative position on the axis of the hanger block

when the portion 31 will be alined with the forward part of the groove 16 and can be moved inwardly and then turned through an angle of 90° to interlock with the overhanging portion 17 and 18. The same 70 method may be employed with the spacing members 32, the portion 34 serving as a hand-hold to move the members into proper operative position in substantially the same manner as described above for the members 75 29. It is obvious that this method cannot be employed for all of the hanger blocks except in the case where the members 15 extend a short distance beyond the point where it is desired to locate the last or the end 80 hanger blocks. In this latter case, it is possible to insert all of the hanger blocks by the hereinbefore described relative turning movement.

The use of the hanger blocks illustrated 85 in Fig. 7, permits of easily and quickly removing a damaged hanger block without the necessity of removing all of the hanger blocks located between the damaged one and the end portion 19 of the member 15, as is 90 necessary in the construction illustrated in Figs. 4 to 6 inclusive.

While I have illustrated and described a refractory member 15, made of electric-insulating material, this is not necessary, as it 95 may be made of a suitable oxidation resistant material, in which case it is necessary to provide means located between the member 15 and the resistor member 27, of electric-insulating material to prevent electric 100 engagement therebetween.

Various modifications may be made in the device embodying my invention without departing from the spirit and scope thereof and I desire that all such modifications shall 105 be included in the appended claims which are to be limited only by the prior art.

I claim as my invention:

1. In an electric furnace, in combination, a member of overhung channel section, and 110 an elongated hanger block interfitting with said member and extending away from the face thereof, and constituting the sole support for a resistor member.

2. In an electric furnace, in combination, a member of overhung channel section, and 115 an elongated hanger block having an end portion interfitting with said member and having a portion extending forwardly therefrom, constituting the sole support for a resistor member.

3. In an electric furnace, in combination, a member of overhung channel section, and 120 a plurality of elongated hanger blocks, each having an enlarged end portion fitting into the member and serving to space the said hanger blocks a predetermined distance apart, and having also a forwardly extending portion constituting the sole support for 125 a resistor member.

4. In an electric furnace, in combination, a member of overhung channel section, and a plurality of elongated hanger blocks, each having an enlarged end portion fitting into the member and serving to space the said hanger blocks a predetermined distance apart, and having also a forwardly extending portion constituting the sole support for a resistor member depending therefrom.
5. In an electric furnace, in combination, a member of overhung channel section, and a hanger block having a relatively narrow and elongated lateral end extension fitting into said member and being insertible in, and removable from, said member, when turned a predetermined amount from the normal position.
6. In an electric furnace, in combination, a member of overhung channel section located in a wall of the furnace, and a hanger block having an enlarged end portion fitting into the groove in said member and having a portion extending forwardly therefrom and constituting the sole support of a resistor member depending therefrom parallel to the wall of the furnace.

In testimony whereof, I have hereunto subscribed my name this 11th day of June, 1925.

JAMES C. WOODSON.
